LOUIS LEHR, OF BRIGHTON HEIGHTS, NEW YORK, ASSIGNOR TO SIMON BRUNER, OF NEW YORK, N. Y.

WATCHCASE CONSTRUCTION.

Application filed November 10, 1924. Serial No. 748,814.

This invention relates to the construction of watch cases, and more particularly to the construction of cases for wrist watches.

An object of this invention is to provide a simple but thoroughly practical construction for wrist watch cases for both ladies' and men's models or styles, particularly such cases of the so-called three-piece type, which construction will be readily adaptable to various shapes, such as the irregular or fancy shapes as are characteristically employed in the design of wrist watches. Another object is to provide a construction of the above nature in which a movement holder of a shape approximating that of the casing itself may be reliably held in position, efficiently accommodated, within the case, readily accessible or removable for repair or inspection, and well protected from injury from the exterior, as well as from ingress thereto of dust or foreign matter. Another object of this invention is to provide a three-piece watch casing, the construction of which will readily lend itself to inexpensive and rapid manufacture, but without detracting from the ruggedness and durability of construction and dependability of action when in use. Another object is to provide a watch casing of the above-mentioned type, but which may be rapidly and inexpensively built up of sections or parts, which lend themselves readily to rapid and inexpensive manufacture. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing, in which is shown one of the various possible embodiments of this invention,

Figure 1 is a perspective view of the several parts of a watch, these parts being shown in detached relation one to another in order to show the construction more clearly;

Figure 2 is a vertical longitudinal section of the parts shown in detached relation in Fig. 1 and taken substantially along the central vertical plane as through the detached parts of Fig. 1; and

Figure 3 is a longitudinal vertical section of the parts of Fig. 1 and Fig. 2 in assembled relation.

Similar reference characters refer to similar parts throughout the several views of the drawing.

As conducive to a clearer understanding of certain features of this invention, it might be pointed out that, in wrist watch construction where the watch itself is often of quite diminutive size, as well as of various irregular or fancy shapes or designs, compactness of construction without sacrifice of ruggedness and durability of construction or without sacrifice of accessibility to the movement itself, is a highly desirable feature toward achieving diminutive size; hence efficiency of housing of the movement within the casing becomes highly important. The ready adaptation or accommodation of a casing of fancy irregular or odd shape to a movement holder of circular or irregular or fancy outline or shape, or vice versa, is among the dominant aims of this invention.

Referring now to the drawing and more particularly to Figures 1 and 2, there is generally indicated at 10 what will herein-after be termed the central frame within which the movement holder is received and mounted; this central frame 10 comprises a plate-like member 11 of sheet metal, having a periphery shaped to correspond to the ultimate fancy shape or design of the watch case as will be clear from Figure 1, and centrally pierced or apertured as at 12. About this opening or aperture 12 there extends a rearwardly directed flange 13 preferably formed integrally with the plate member 11. The aperture 12 and hence the flange 13 is preferably of a shape corresponding to that of the movement holder itself; the latter is indicated in Figure 1 at 14 and as there shown is of an elliptical shape thus to closely approximate the general contour of the outer casing construction itself. The member 11 with its opening 12 and flange 13, it will be noted, may be rapidly and inexpensively struck up as in the usual form of punch press, for example.

The movement holder 14 is supported within the plate member 11 by means of a second plate-like member 15, the periphery of which, as will be clear from Figure 1, has a shape corresponding substantially

to the fancy outline above-mentioned, and is held in spaced relation (as is clearly shown in Fig. 2) with respect to the plate-like member 11 by means of a flange 16 preferably integrally formed with the plate-like member 15. The latter is apertured as at 17, this aperture corresponding in shape to the shape of the movement holder 14 which, as above noted, is shown, by way of example, 10 as of elliptical shape. Preferably the apertures 17 and 12 are aligned and of like shape so that the movement holder 14 may be fitted within these apertures, as will be clear from a consideration of Figure 3, 15 it being noted that the movement holder 14 is provided about its upper periphery with a projecting flange 18 for limiting the downward movement of the holder 14 with respect to the central frame 10. The 20 aperture 17, and preferably also the aperture 12, are so dimensioned that the movement holder 14 is received therein with a slight force-fit, thus to hold the movement holder 14 securely in position. The plate 25 members 11 and 15, being secured together by soldering, for example, of the flange 16 to the plate member 11 thus will encase the movement holder 14 about its periphery, but leave exposed, for inspection 30 or repair, the front and back respectively of the movement holder 14.

At one side of the flange 16 (see Fig. 1) there is provided a suitable opening 19 through which the stem 20 of the movement 35 holder 14 may be inserted as the latter is inserted within the central frame 10, the crown 21 being placed upon the stem 20 after the assembly of these parts.

A back cover, generally indicated at 22 40 (see Fig. 1) is provided for closing the rear side of the frame 10; this back cover 22 is, like the remaining parts of the casing, built up of parts which lend themselves to rapid and inexpensive manufacture. This back 45 cover 22 comprises preferably two members, the one comprising a flat sheet metal member 23, the extreme outer periphery of which is given the fancy outline desired, but is substantially centrally apertured as at 24. The 50 other member of this back cover 22 comprises the sheet metal member 25, having the fancy outline; it is preferably flanged throughout its periphery, as will be clear 55 from Figures 2 and 3, and the co-mating peripheries of the parts 25 and 23 are suitably secured together as by soldering. The aperture 24 of this back cover 22 is of such size as to fit and snap over the flange 13 of the plate-like member 11 of the central 60 frame 10.

The front cover comprises preferably a sheet metal member 26, also of the fancy outline; it is apertured as at 27 in any desired shape so as to receive and hold, by any convenient means, a crystal 28 of corresponding

shape; and is provided with a peripherally extending and rearwardly directed flange 29 shaped to fit and snap over the plate-like member 15, and the peripheral flange 16 of the latter. The front cover 26 is suitably cut away at the side thereof, as at 30, in order to accommodate the stem 20 of the movement holder 14, and as will be seen from Figure 3, the flange 29 is snugly fitted over the flange 16 of the central frame 10 and is seated against the plate-like member 11 of the latter.

While the front and back covers are securely held in assembled relation with respect to the central frame 10, yet I prefer to connect these three parts together as by a suitable hinge construction. The latter may comprise suitable tubular sections 31^a (secured as by soldering to the flange 29 of the front cover 26), 31^b (secured as by soldering to the plate member 11), and 31^c (secured as by soldering to the sheet metal member 23 of the back cover 22). These tubular sections are laterally displaced, so that they may be brought into axial alinement for the passage therethrough of a suitable connecting pin, the snap fits of the front and back covers to their respective portions of the central frame 10 acting to hold these parts in closed relation. Suitable loops 32 and 33, suitably secured to the front cover 26, are provided for attaching a suitable band or strap for holding the watch in position.

The assembled parts are shown in Figure 3, and in view of the foregoing description of the construction and assembly of the detail parts of the construction provided in this invention, it is believed that the features of this invention will be readily understood; it may be noted, however, that the construction provided in this invention permits the rapid and inexpensive building up of the several parts of the watch casing out of sections of sheet metal which sections of themselves lend themselves to great rapidity of manufacture, thus making for not only speed of production, but also inexpensive manufacture as a whole. The parts may, for example, be readily struck up, and it will be seen that to accommodate within a casing of one character of fancy shape or outline a movement holder approaching this outline, it is merely necessary to pattern the aperture 17, and as desired in the preferred construction, the aperture 12 (see Figs. 1 and 2) according to the shape of the movement holder desired or most appropriate to the shape of the casing itself. Moreover, it will be noted that there has been provided in this invention a construction in which foreign matter is effectively excluded from access to the movement holder itself, the manner in which the front and back covers inter-fit with the central frame providing relatively long joints along which it is exceedingly difficult,

if not impossible, for foreign matter to move. It will moreover be noted that there is provided in this invention a watch casing construction in which the several objects hereinbefore noted, as well as others, together with many thoroughly practical advantages are successfully achieved.

As many possible embodiments may be made of the above invention, and as many changes might be made in the embodiment above set forth, it is to be understood that all matter hereinbefore set forth is to be interpreted as illustrative and not in a limiting sense.

15 I claim as my invention:

1. In watch casing construction, in combination, a central frame formed of two sheet metal members held in spaced relation with respect to one another, both of said members being substantially centrally apertured to provide substantially aligned openings in which to receive a movement holder, a flange about the periphery of one of said members for holding it in spaced relation from the other member, and a flange about the periphery of the opening in one of said members; a cover for said frame member having a flange adapted to fit over said first-mentioned flange; and another cover for said frame member having means adapted to fit and snap over said second-mentioned flange.

2. In watch casing construction, in combination, a central frame built up of two sheet metal members, each of which has a fancy outline and the front member of which is apertured to receive a movement holder of a shape approximating that of the fancy outline, means for rigidly connecting together but holding in spaced relation said two members, and a rearwardly directed flange on the rear one of said two members but within the outer periphery of said member; a front cover for said frame having a like fancy outline and a flange extending thereabout for fitting and snapping over the front member of said central frame; and a back cover for said frame having means adapted to fit and snap over said rearwardly directed flange of said rear member of said central frame.

3. In watch casing construction, in combination, a plate-like sheet metal member having a rearwardly directed flange but positioned within the periphery of said member, a back cover having means adapted to fit and snap over said flange to hold said cover to said member, means for supporting a movement holder upon said plate-like member comprising a second plate-like sheet metal member apertured to receive said holder but supported in spaced relation from said first plate-like member, and a front cover having a peripheral flange adapted to

fit and snap over said first-mentioned plate-like member.

4. In watch casing construction, in combination, a plate-like sheet metal member having a rearwardly directed flange but positioned within the periphery of said member, a back cover having means adapted to fit and snap over said flange to hold said cover to said member, means for supporting a movement holder upon said plate-like member comprising a second plate-like sheet metal member apertured to receive said holder but supported in spaced relation from said first plate-like member, by means of a peripherally extending flange on one of said plate-like members, and a front cover having a peripheral flange adapted to fit and snap over said plate-like member.

5. In watch case construction, in combination, a central frame formed of two sheet metal members of fancy outline and held in spaced relation by means of a peripherally formed flange on one of said members, both of said members being centrally apertured to provide substantially aligned openings in which to receive and hold a movement holder and one of said members being provided with an upstanding flange but within the periphery of said member; a cover for one side of said frame having a flange adapted to fit and snap over one of said flanges to hold said cover in place; and a cover for the other side of said frame having means adapted to fit and snap over the other of said flanges.

6. In watch casing construction, in combination, an apertured plate-like member of fancy outline having a rearwardly directed flange but positioned within the periphery of said member; a back cover of fancy outline adapted to rest against the rear side of said member and having means adapted to fit and snap over said flange, means for supporting a movement holder upon said plate-like member comprising a second plate-like member apertured to receive said holder but supported in spaced relation from said first plate-like member, said second-mentioned plate-like member having substantially the same fancy outline as said first-mentioned plate-like member but within the compass thereof; and a front cover of substantially the same fancy outline but provided with a peripherally extending flange adapted to fit and snap over said second-mentioned plate-like member and to rest against said first-mentioned plate-like member.

In testimony whereof, I have signed my name to this specification this 6th day of November, 1924.

LOUIS LEHR.
